United States Patent Office.

BENJAMIN G. LUTHER, OF PROVIDENCE, RHODE ISLAND.

Letters Patent No. 91,551, dated June 22, 1869.

IMPROVED FOLDING WAGON-COVER FRAME.

The Schedule referred to in these Letters Patent and making part of the same.

To all whom it may concern:

Be it known that I, BENJAMIN G. LUTHER, of Providence, in the county of Providence, and State of Rhode Island, have invented an Improved Folding Wagon-Cover Frame; and do hereby declare that the following is a full and exact description, reference being had to the accompanying drawings, making a part of this specification.

The nature of my invention consists in connecting the two outer bows of a wagon-cover frame by means of toggle-levers, which will allow the cover to be folded up in a small space, and at the same time hold it perfectly rigid, at its full extent, when in use upon the wagon.

To enable those skilled in the art to make and use my invention, I will proceed to describe its construction and operation.

Figure 1 represents a side view;

Figure 2, an end view; and

Figure 3, an interior side view.

The two outer bows, A' and A, are connected to each other, on each side, by means of the toggle-levers B' B' and B B, as shown; the joints b' and b being secured to each other by the clasp C, which may be

made of metal, to spring over the pin c, as shown, or it may be a leather strap, or the joints b' and b may be secured directly to the middle bow D, by means of thumb-screws or other convenient devices.

The bows at the top and bottom of each side are secured to each other by the flexible straps E' and E.

These straps serve to secure the outer covering from excessive strain, when extended to its extreme limit.

The opposite ends of the bows, at the bottom, are held from springing apart by the metallic strap F.

In folding the cover, the joints b' and b are to be loosened from their fastenings, when the bows can be pressed directly back against each other, so as to occupy but little space for storage.

What I claim as my invention, and desire to secure by Letters Patent, is—

The combination of the two outer bows with the toggle-levers B' B' and B B, secured to the middle bow D by appropriate clasps, substantially as described.

B. G. LUTHER.
